UNITED STATES PATENT OFFICE.

SIMON LOEWENTHAL, OF NEW YORK, N. Y., ASSIGNOR OF ONE-HALF TO
ABRAHAM B. LEVY, OF SAME PLACE.

NURSING-VEST.

SPECIFICATION forming part of Letters Patent No. 269,504, dated December 19, 1882.

Application filed September 23, 1882. (No model.)

To all whom it may concern:

Be it known that I, SIMON LOEWENTHAL, a citizen of the United States, and a resident of New York, in the county of New York and State 5 of New York, have invented a new and valuable Improvement in Nursing-Vests; and I do hereby declare that the following is a full, clear, and exact description of the construction and operation of the same, reference being had to 10 the annexed drawing, making a part of this specification, and to the letters and figures of reference marked thereon.

The figure of the drawing is a representation of my invention.

15 This invention has relation to nursing under-vests for women; and it consists in the construction and novel arrangement of the breast-openings made entirely below the neckband, and each provided with an elliptically-shaped 20 or elongated flap or covering-piece, which is securely stitched to one side of the opening, and is free at its opposite edge, and provided with button-holes, whereby it may be attached to buttons on the opposite side of the open- 25 ing.

30 The invention also consists in providing the covering piece or flap with elastic loops, which are designed to be attached to said buttons during the nursing period, all as herein- 35 after set forth.

In the accompanying drawing, the letter *a* designates a woman's under-vest, in which are made the vertical openings *b* for the breasts, these openings being entirely below the neck- 40 band and not communicating therewith.

To one side of each opening is secured one edge of an elongated or elliptical flap, *c*, which is first bound with silk or other suitable binding to prevent fraying. The other edge, *d*, of 45 this flap is provided with button-holes *e*, which are designed to be attached to the buttons *g*, which are secured in corresponding position to the corresponding edge, *h*, of the breast-opening *b* of the vest, the edge *h* being also provided with binding or hemmed to prevent fraying.

In juxtaposition to each button-hole *e* of the flap or covering-piece *c* is secured to the edge of said flap a loop, *l*, of elastic or rubber cord,

which is designed to be used in connecting this 50 edge of the flap to the buttons *g* during the nursing period, when the breasts are in a swollen condition.

The advantages of this construction relate to the health and convenience of the nursing- 55 woman and the child. It is designed to avoid uncovering the breasts except to the limited extent required in nursing. The breasts of the woman are kept at all times warm and thoroughly protected, while she is enabled to 60 suckle the child with ease and without exposure. It is designed to give more comfort to the child as well as to the mother during this period. The elastic loops provide extra room under the flap for the breast when it becomes 65 enlarged during the nursing period. At any other time the vest can be more closely fastened by means of the button-holes *e*. An in- 70 dependent central opening, *z*, from the neck- band downward, furnished with buttons and button-holes in the ordinary manner, is pro- 75 vided to facilitate the removal of the vest or putting on the same.

A corset having triangular slits in its upper 75 edge, said slits opening through the upper edge, and two series of buttons in a line parallel to said upper edge between the slits, has been provided with triangular covering-flaps stitched to the outer edges of the slits, and provided with button-holes at their upper cor- 80 ners for engaging the series of buttons prior to my invention, and I do not claim said construction herein.

Having described this invention, what I claim, and desire to secure by Letters Patent, 85 is—

1. A woman's under-vest having the vertical breast-openings *b* made entirely below the neckband, and each provided with an elongated flap or cover-piece, *c*, securely stitched 90 to one side of the opening, and provided in its opposite free margin with button-holes *e*, whereby it may be connected with corresponding buttons, *g*, on the opposite side of the opening, substantially as specified.

2. A woman's under-vest having the vertical breast-openings *b* made entirely below the neckband, and provided with the flaps or

cover-pieces *c*, each fastened by one edge to one side of each opening, and provided with button-holes *e* and elastic loops *l*, for vicarious use in connecting the free edge of said flaps or cover-pieces to the buttons *g* of the opposite edges of the openings, substantially as specified.

In testimony that I claim the above I have hereunto subscribed my name in the presence of two witnesses.

SIMON LOEWENTHAL.
